[57] ABSTRACT

A detergent composition having controlled foaming and rinsing properties containing an anionic surface active agent and from 1 – 40 wt. percent of fatty acid salt of the formula

wherein R₁ is alkyl (10 – 24 C), R₂ is alkyl (1 – 8 C) and the total number of carbon atoms of R₁ and R₂ is 11 – 25, n is 0 or 1 and M is an alkali metal.

3 Claims, No Drawings

CONTROLLED FOAMING DETERGENT COMPOSITIONS

This is a continuation, of application Ser. No. 206 498, filed Dec. 9, 1971.

BACKGROUND OF THE INVENTION

1. Field of the Invention

The present invention relates to controlled foaming detergent compositions containing special foam inhibitors.

2. Description of the Prior Art

Branched chain sodium alkylbenzenesulfonates (hereinafter referred to as ABS) have been used heretofore as surfactants which are the main active ingredients of household detergents. However, in the detergents containing ABS, foaming during washing is very strong and a long time is required, after washing is completed, for rinsing the clothes in clean water. For facilitating rinsing, 10 - 20 wt. percent, based on the weight of ABS, of sodium salts of straight chain fatty acids (mainly sodium stearate) have been incorporated in the detergent compositions. The foam-controlling effect of sodium stearate on ABS is excellent and the rinsing after the washing has been made very easy.

However, recently, the pollution of rivers due to ABS has posed an environmental problem and, accordingly, surfactants decomposable by microorganisms have been developed. There have been found as such decomposable surfactants, straight chain alkylbenzenesulfonates, monoalkyl sulfuric acid ester salts, α -olefin-sulfonic acid salts and alkane sulfonic acid salts. However, although said decomposable surfactants show quite excellent deterging powers, no notable foam-controlling effect, like the one obtained with ABS, can be obtained by adding thereto sodium stearate. Thus, there remains a problem in the rinsing of such decomposable detergents from clothes.

In view of these circumstances, the development of a detergent decomposable by microorganisms and having a controlled foaming property (like the one obtained by adding sodium stearate to ABS) without lowering the deterging power has been desired and various investigations have been made. An excellent foam inhibitor for this purpose, however, has not been developed to date.

An object of the present invention is to provide a detergent composition containing surfactants decomposable by microorganisms or branched chain alkylbenzene sulfonates and, in addition, compounds having an effective foam-controlling property for various anionic surface active agents.

Another object of the invention is to provide foam-controlled detergent compositions containing such foam inhibitors.

SUMMARY OF THE INVENTION

The objects of the present invention can be accomplished by providing detergent compositions containing one or more anionic surface active agents and a fatty acid salt of the following general formula (1)

(1)

wherein R_1 is an alkyl group of 10 - 24 carbon atoms, R_2 is an alkyl group of 1 - 8 carbon atoms and the total number of carbon atoms of R_1 and R_2 being 11 - 25, n is 0 or 1 M is an alkali metal, such as sodium or potassium.

Examples of said fatty acids are propanoic acid containing an alkyloxy or alkyloxymethyl group of 10 - 24 carbon atom in the α -position, butanoic acid containing an alkyloxy or alkyloxymethyl group of 10 - 23 carbon atoms in the α -position, pentanoic acid containing an alkyloxy or alkyloxymethyl group of 10 - 22 carbon atoms in the α -position, hexanoic acid containing an alkyloxy or alkyloxymethyl group of 10 - 21 carbon atoms in the α -position, heptanoic acid containing an alkyloxy or alkyloxymethyl group of 10 - 20 carbon atoms in the α -position, octanoic acid containing an alkyloxy or alkyloxymethyl group of 10 - 19 carbon atoms in the α -position, nonanoic acid containing an alkyloxy or alkyloxymethyl group of 10 - 18 carbon atoms in the α -position and decanoic acid containing an alkyloxy or alkyloxymethyl group of 10 - 17 carbon atoms in the α -position.

Of course, these fatty acids salts may be used in the form of a mixture of two or more fatty acid salts or together with other fatty acid salts such as a stearate.

The fatty acid salts of above general formula (1) can be produced easily on an industrial scale. For example, the acids of formula (1) in which n is 1 can be produced by adding a higher alcohol to a methacrylic acid ester and hydrolyzing the resulting product. The acids of formula (1) in which n is 0 can be produced by reacting an α -halogeno-propionic acid with a higher sodium alcoholate or by reacting lactic acid with an alkyl halide in the presence of metallic sodium.

The detergent compositions of the present invention contain anionic surface active agents and, if desired, other conventional detergent ingredients, i.e., builders.

The anionic surface active agents used in the present invention are those used as starting surfactants for general purpose household detergents such as an alkylbenzenesulfonate salt containing a straight chain alkyl group of 10 - 18 carbon atoms, an alkyl sulfuric ester salt of 12 - 18 carbon atoms, an α -olefin sulfonic acid salt of 14 - 20 carbon atoms, an alkane sulfonic acid salt of 12 - 20 carbon atoms, a sulfuric ester salt of polyoxyethylene (1 - 10 oxyethylene units) alkyl (C_{12} - C_{18}) ether or sulfuric ester salt of polyoxyethylene (1 - 10 oxyethylene units) alkylphenyl (C_8 - C_{12}) phenyl ester and mixtures of them. ABS may be included therein. Builders are neutral or alkaline inorganic salts such as polyphosphoric acid salts, sodium sulfate, sodium carbonate, water-soluble sodium silicate and sodium borate and water-soluble organic builders such as sodium nitrilotriacetate, sodium succinate, sodium salt of carboxymethylcellulose and polyethyleneglycol.

The amount of the fatty acid salts of formula (1) in the detergent composition of the present invention varies depending on the proportions of the anionic surface active agents contained in the detergents. Generally, the suitable amount of the fatty acid salts is within the range of 1 - 40 wt. percent, based on the amount of anionic surface active agent contained in the detergent compositions. Of course, the fatty acid salts may be contained in a larger amount, but this is uneconomical.

The generally used heavy duty detergent composition, according to the invention, comprises 5 - 40 wt. percent of a surfactant, 0.1 - 15 wt. percent of a foam

controller (fatty acid salt-formula (1)) and 94.9 - 45 wt. percent of builder and other conventional detergent ingredients. Such conventional detergent ingredients are perfumes (usually in an amount of 0.01 to 1% by weight) and optical brighteners (usually in an amount of 0.1 to 1% by weight), etc., which will be used as required.

The compositions of the present invention are effective, especially as heavy duty detergents, owing to their quite excellent deterging power and particularly foam-suppressing effect. The rinsing property of the detergent composition is thus highly improved.

The various effects of the compositions of the present invention will be illustrated in the following illustrative Examples.

EXAMPLE 1

Detergent compositions of the following general formula were prepared.

Parts by weight	
Surfactant (see Tables 1 and 2)	20
Foam controller (see Tables 1 and 2)	2
Sodium tripolyphosphate	35
Sodium silicate	3
Sodium carbonate	3
Sodium salt of carboxymethylcellulose	1
Sodium sulfate	26
Water	10

Each granular synthetic detergent composition comprising the above ingredients was dissolved in city water to obtain a solution of a detergent concentration of 0.2 wt. percent. The solution (100 cc.) was placed in a cylinder of a diameter 64.5 mm. An automatic reverse stirrer (a product of Irie Seisaku-sho, R 101) rotatable at 1450 rpm. having four stirring blades of 50 mm length and 12 mm width was placed just below the surface of the test solution. The solution was stirred for 6 minutes and the volume of foam was measured. Thereafter, the lower aqueous layer was taken out and 100 cc. of city water were added to the remainder (foam) in the cylinder and treated in the same manner as above. The water in the lower layer was taken out. These procedures were repeated until the foam disappeared. The total quantity of water used was measured. The results are shown in Tables 1 and 2.

TABLE 1

Effects of foam controller (sodium salts of ether fatty acids) on the rinsing properties of detergent compositions containing straight chain sodium dodecylbenzenesulfonates as the surfactant.

n	Foam controller	Foam- ing	Quan- tity of water
0	Sodium α -myristyloxypropionate	270	400
	Sodium α -stearyloxypropionate	80	400
	Sodium α -docosyloxypropionate	80	400
1	Sodium α -lauryloxyethylpropionate	270	400
	Sodium α -myristyloxyethylpropionate	270	300
	Sodium α -stearylloxyethylpropionate	200	400
Control	Sodium stearate	270	700
	No additive (foam controller was replaced by water)	275	800

TABLE 2

Effects of sodium α -myristyloxyethylpropionate on the rinsing properties of detergent compositions containing various anionic surface active agents.

Surfactant	Foam controller	Foaming	Quantity of water
Sodium dodecylsulfate	not added	280 ml	900 ml
Sodium α -olefinsulfonate (average carbon number 16)	added	120	300
	not added	300	800
Sodium alkanesulfonate (average carbon number 16)	added	100	400
	not added	280	700
	added	100	400

The data in Tables 1 and 2 clearly show that the foam controllers of the present invention have excellent foamcontrolling effects. Particularly, the use of the foam controllers of the present invention together with straight chain alkylbenzenesulfonates yields detergents of great foaming property at the time of the deterging and easy rinsing effects.

EXAMPLE 2

Straight chain sodium dodecylbenzenesulfonate was mixed with sodium α -myristyloxyethylpropionate in various proportions. The rinsing properties of 0.2 wt. percent solutions in the resulting mixtures were measured in the same manner as in Example 1. The results are shown in Table 3.

35

Table 3

Straight chain sodium dodecylbenzenesulfonate	Sodium α -myristyloxyethylpropionate	Foaming	Quantity of water
100 wt.%	0 wt.%	275 ml	800 ml
99	1	270	600
90	10	270	400
75	25	250	300
60	40	240	300

45

The data in Table 3 show that the rinsing effect can be improved remarkably by incorporating in the detergent compositions a small amount of sodium α -myristyloxyethylpropionate.

EXAMPLE 3

55

Detergent ingredients		wt.%
Straight chain sodium dodecylbenzenesulfonate		25
Sodium α -myristyloxyethylpropionate or		2
sodium stearate		25
Sodium tripolyphosphate		5
Sodium silicate		32
Sodium sulfate		1
Sodium salt of carboxymethylcellulose		10
Water		

The deterging power of a 0.2 wt. percent solution of the above detergent composition was tested. No differ-

ence in deterging power was found between the formula containing sodium α -myristyloxymethylpropionate and a control formula containing sodium stearate.

EXAMPLE 4

Detergent ingredients	wt. %
Straight chain sodium alkylbenzene-sulfonate (average carbon number 13)	20
Sodium α -myristyloxymethylpropionate or sodium stearate	2
Sodium tripolyphosphate	20
Sodium silicate	5
Sodium sulfate	41
Sodium salt of carboxymethylcellulose	1
Sodium carbonate	1
Water	10
	15

The practical tests of the foaming power and the rinsing property of granular synthetic detergent compositions comprising the above ingredients were carried out by using an electric washing machine.

In an electric washing machine were placed 25 liters of city water (25°C.) and 50 g of the detergent of the above composition and the contents were stirred for 1 minute. The heights of the resulting foams were measured.

Then, two pieces of shirt and two sheets of knitted good (total weight 830 g) were introduced therein and the whole was stirred for 4 minutes. The heights of the resulting foams were measured. The stirring was continued for an additional 5 minutes and the heights of the foams were measured again. After the washing, the washed goods were wrung with an attached squeezer. The presence or absence of foams was examined and the wash solution was discharged. The washings were again stirred together with 25 liters of fresh water for one minute and wrung. The presence or absence of foams was examined and the water was discharged. Thereafter, the presence or absence of foams at the bottom of the washing machine was confirmed. If the foams still remained, the procedures from introduction of water to the discharging thereof were repeated. In the following table, the "times of rinsing" means the number of times the cycle was repeated. The results are shown in Table 4.

Table 4

Foam controller	Height of foams (mm)			Times of rinsing
	1 min.	4 mins. (5 mins. in total)	5 mins. (10 mins. in total)	
Sodium α -myristyloxymethylpropionate	20	40	50	1.5
Sodium stearate	20	50	70	3
No additive	30	60	90	4

The data in Table 4 show that in the composition of the present invention containing sodium α -myristyloxymethylpropionate, defoaming can be effected by only one rinsing or a little more. The compound is thus superior to sodium stearate.

The embodiments of the invention in which an exclusive property or privilege is claimed are defined as follows:

1. A controlled foaming detergent composition consisting essentially of

A. from 5 to 40 percent by weight of anionic surface active agent selected from the group consisting of alkylbenzenesulfonate salts having a straight or branched chain alkyl group of 10 to 18 carbon atoms, alkyl sulfuric ester salts of 12 to 18 carbon atoms, α -olefin sulfonic acid salts of 14 to 20 carbon atoms, alkane sulfonic acid salts of 12 to 20 carbon atoms, sulfuric ester salt of polyoxyethylene (1-10 oxyethylene units) alkyl (C_{12} - C_{18}) ether, sulfuric ester salt of polyoxyethylene (1-10 oxyethylene units) alkyl (C_8 - C_{12}) phenyl ether and mixtures thereof,

B. from 0.1 to 15 percent by weight of fatty acid salt or mixture of fatty acid salts of the formula:

wherein R_1 is an alkyl group of 10-24 carbon atoms, R_2 is an alkyl group of 1-8 carbon atoms and the total number of carbon atoms of R_1 and R_2 is 11-25, n is 0 or 1 and M is an alkali metal, provided further that the amount of said fatty acid salt or mixture of fatty acid salts is from 1 to 40 percent by weight, based on the weight of said anionic surface active agent,

C. and the balance is builder selected from the group consisting of sodium tripolyphosphate, sodium sulfate, sodium carbonate, water-soluble sodium silicate, sodium borate, sodium nitrilotriacetate, sodium succinate, sodium salt of carboxymethylcellulose and polyethylene glycol and mixtures thereof.

2. A controlled foaming detergent according to claim 1, in which ingredient B is selected from the group consisting of

sodium α -myristyloxypropionate
sodium α -stearylloxypropionate
sodium α -docosyloxypropionate

sodium α -lauryloxymethylpropionate
sodium α -myristyloxymethylpropionate
sodium α -stearylloxymethylpropionate.

3. A controlled foaming detergent according to claim 1, in which ingredient B is sodium α -myristyloxymethylpropionate and ingredient A is straight chain sodium dodecylbenzenesulfonate.
